<img alt="Wiring diagram for a vintage car radio and heater system. The diagram shows a 12V battery connected to a radio (IC) and a heater control unit. The radio is connected to a speaker and a horn. The heater control unit includes a 3-position switch, a 12V relay, and a 12V heater. Various wires are labeled with numbers such as 85, 75, 79, 80, 84, 77, 83, 78, 82, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, By Curtis B. Camp
Attorney

UNITED STATES PATENT OFFICE.

WILLIAM KAISLING, OF CHICAGO, ILLINOIS, ASSIGNOR TO KELLOGG SWITCHBOARD AND SUPPLY COMPANY, OF CHICAGO, ILLINOIS, A CORPORATION OF ILLINOIS.

COMBINED LIGHTING AND IGNITION SWITCH.

Application filed December 15, 1913. Serial No. 806,752.

To all whom it may concern:

Be it known that I, WILLIAM KAISLING, a citizen of the United States of America, residing in Chicago, county of Cook, and State of Illinois, have invented certain new and useful Improvements in Combined Lighting and Ignition Switches, of which the following is a specification.

My invention relates to electrical switches in general and has to do more particularly with so-called combination lighting and ignition switches ordinarily used on automobiles. That is unit switches of that character wherein a single frame-work is provided for supporting the switch mechanisms for controlling the ignition and lighting circuits. In devices of this character it is important that the control of the different circuits be automatic so far as possible and that the number of operations be reduced to a minimum and to this end I have provided a device of the above character having two operating levers for controlling the lighting and ignition circuits respectively together with a third or starting switch which is also controlled by the actuating member of the ignition switch. Another object of my invention is to provide a switch of the above character in which a so-called dimmer switch is combined with the lighting switch for controlling the brilliancy of the lights. A further object of my invention is to provide a device having the above characteristic, which is compact, easily accessible to all of its working parts, and positive in its operation.

Referring now to the accompanying drawing in which I have illustrated my improved structure,

- Fig. 1 is a face view of my invention;
- Fig. 2 is a right side elevation of Fig. 1;
- Fig. 3 is a rear view of Fig. 1;
- Fig. 4 is an interior face view of the mechanism with the cap removed;
- Fig. 5 is a left side elevation of Fig. 4;
- Fig. 6 is a right side elevation of Fig. 4;
- Fig. 7 is a top view of Fig. 4;
- Fig. 8 is a sectional view through the lighting switch L showing wiper members removed from their supporting shaft.

Fig. 9 is a sectional view along the line 9, 9 of Fig. 12 to show the method of operating the horn cut-out by the lock;

Fig. 10 is a sectional view along the line 10, 10, of Fig. 4 to show the method of construction of one of the contact blades of the lighting switch.

Fig. 11 is a partial view of Fig. 4 showing the starting switch SS in an operated position, effected by means of the ignition switch M;

Fig. 12 is a view of the middle part of Fig. 4 but with parts of the apparatus removed to more clearly show the locking arrangement, the operating levers being at normal and unlocked;

Fig. 13 is similar to Fig. 12 but showing the locking mechanism in operated position;

Figs. 14 and 15 illustrate the contacting segments of the lighting switch showing the normal and operated positions of the wiper blades in dotted lines.

Fig. 16 illustrates the dimmer and starting switch contacts;

Figs. 17 and 18 illustrate the contact segments of the ignition switch and show the normal and operated positions of the wiper in dotted lines;

Fig. 19 illustrates the locking winding cut-out contacts of the starting switch.

Fig. 20 is a sectional view along the line 20, 20, of Fig. 4 showing the construction of the yielding holding member.

Fig. 21 is a vertical sectional view through the locking mechanism;

Fig. 22 is a sectional view along the line 22, 22, of Fig. 5 illustrating the construction of the dimmer switch and

Fig. 23 illustrates diagrammatically a circuit adapted to operate in connection with the switch as shown.

Referring now in general to my invention as illustrated it comprises a lighting switch L and an ignition switch M, the lighting switch having a normal position A and preferably three operative positions B, C and D whereby three combinations of lights can be connected in circuit. The arrangement of the lighting switch is such that when its operating lever is moved to the

- position B, the side, tail and speedometer lights are lighted and when the operating lever is moved to the position C, the head, tail and speedometer lights are lighted.
- 6 Now when the operating lever is thrown to its position D which is the last position, all of the lights are lighted, but I do not wish to be limited to this particular arrangement as many different combinations can be
- 10 made without departing from the invention.

The ignition switch M rests normally in an inoperative position E it having preferably two operative positions F and G as shown, and when the ignition switch is moved into its position F the battery ignition is in use and when moved into its position G the magneto ignition is in use.

A starting switch SS (Figs. 4-11) is also provided which is used with a uni-spark system as illustrated in Fig. 23 but when the starting switch is operated it converts the uni-spark system into a vibratory system to throw a shower of sparks to give an effective starting circuit. This starting switch is also arranged so as to close a circuit for a starting motor to start the engine such as is used in the well-known Delco self-starting system.

I also provide a dimmer switch DS which is operated by turning a knob to the left or right and when the dimmer switch is in its normal or effective position, (in which position the wiper is not engaging its contacts) the current is carried through a resistance which reduces the current flow through the head lights dimming them. When the wiper of the dimmer switch is thrown into its operative position to engage its contacts it short circuits the resistance and allows the full current flow to pass through the head lights giving them their full candle power.

I also provide a locking mechanism which consists preferably of a standard Yale tumbler lock which controls two sliding plates which are adapted to lock the lighting and ignition switches, the dimmer switch, and also a horn cut-out. The locking mechanism is so arranged that it operates only when the switch M is in its normal or inoperative position E, and when the ignition switch lever is in either its F or G position the lock cannot be turned by the key. Now if the operator attempts to operate the lock he is at once aware that the ignition switch is in an operative position and must be moved to its inoperative position E so that the lock can be operated and the key withdrawn.

The locking arrangement of the lighting switch is so constructed that the key may be turned to lock the lighting switch in any of its lighting positions so that the operator can leave any combination of lights lighted and still lock the lighting switch against operation.

The starting switch SS is also controlled against operation as it is preferably worked in combination with the ignition switch and therefore cannot be operated when the ignition switch is locked in its inoperative position.

The dimmer switch DS may also be locked in either its effective or non-effective position by the same lock and key and when the lighting switch is locked in any of its operated positions, the said dimmer switch is also locked against operation.

A horn cut-out 11C (Fig. 9) is also controlled by the said locking mechanism and when the lock is in its unlocked position the horn is in circuit but when the lock is operated to lock the switch the horn circuit is opened.

Referring now more in detail to my invention as illustrated, it comprises preferably a mounting base or plate 1 made of suitable insulating material and having studs 2 and 2¹ fastened to it in any suitable manner preferably as illustrated in Fig. 8, said studs having a portion extending through the plate 1 threaded to receive the nut 3. A stud 2 is provided for the lighting switch L and a stud 2¹ for the ignition switch M.

The lighting switch L comprises a shaft 4 having a bearing 5 and carrying a wiper 6 which is insulatingly mounted on the shaft 4, the said wiper comprising blades 6¹ and 6² which are clamped upon the shaft 4 by means of a nut 7. The blade 6¹ as clearly illustrated in Fig. 10, has its top and bottom surfaces made up of two segments 6³ and 6⁴, said segments being insulatingly mounted; rivets 6⁵ passing through the insulating bushings, but not electrically connecting the segments 6³ and 6⁴, this wiper blade is constructed so as to operate with the dimming of the head lights, as will be more fully described in other parts of the specification.

I provide a yielding holding device for holding each of the switches in their different positions this holding device being in the form of a notched or toothed disk 8 which is also firmly clamped upon the shaft 4 by means of the nut 7. To hold the disk 8 and the wiper 6 in the same relative positions, I provide a pin 9 which is forced through the disk 8 and insulated from the wiper 6 by a bushing. When the lighting switch is in place on the stud 2 it rests against the plate 1.

Co-operating with the wiper blades 6¹ and 6² of the light switch L are the segmental contact strips 10, 11, 12, 13, and 14 as illustrated in Figs. 14 and 15. The segments 10, 11, 12, 13 and 14 have extensions 10¹, 11¹, 12¹, 13¹, 13² and 14¹ in the form of contact ends which operate in connection with the wiper blades 6¹ and 6² to give the different combination of lights. The segment 13 is common having the extensions 13⁰

13¹ and 13² which are related to the contact strips 10¹ and 11¹. The contact ends 10¹, 11¹ and 12¹ operate in connection with the top surface of the wiper blades 6¹ and 6² and the said segments 10, 11, 12 being connected to their respective terminals 10², 11² and 12², shown in Fig. 3. The contact ends 13¹, 13² and 14¹ operate in connection with the bottom blades or surfaces 6³, 6⁴ of the wipers 6¹ and 6². The strip 13 carries contact ends 13¹, 13² and is connected to the terminal 13³ through the clamping screw 15 and strip 15¹. The segment strip 14 has an extending portion 14² arcuate in shape which operates in connection with the dimmer switch wiper 16, the strip 17 also co-operating with said wiper which is adapted to connect the two elements 14², 17. Segmental contact strip 17 is connected to the common strip 13 by a metal washer 18 as illustrated in Fig. 16. The member 14 has an ear 14³ which carries a stud 19 tapped to receive the screw 20 which serves as a binding post for one of the terminals of the resistance element 21, the other terminal of the resistance being fastened to the common strip 13 by means of the clamping screws 15, (Fig. 4). The strip 13 has an extension 13⁴ (Fig. 16) operating in connection with a contact strip 49, the said contact strips 13⁴ and 49 operating in connection with wiper 31 of starting switch SS. Now when the lighting switch is in its normal position A, there is no connection between the wiper blades and the contact segments but when it is moved to its position B the contact segments 10¹, 11¹, 13¹, 13² are connected as shown in Figs. 14 and 15 giving one combination of lights. Now if the lighting switch is moved to its position C, the contact segments 11¹, 12¹, 13², 14¹ are connected as shown in Figs. 14 and 15 giving a second combination of lights, and when the lighting switch is moved to its position E the contact segments 10¹, 11¹, 12¹, 13² and 14¹ are connected as shown in Figs. 14 and 15 giving the third combination of lights.

Referring now to the ignition switch M, this is similar in construction to the lighting switch L except that the notched disk 8¹ differs, as does the wiper 22, said wiper having one wiper blade 22¹. In addition, the shaft 4¹ carries a cam 23 which operates in connection with the starting switch and which will be more fully described in another part of the specification. Corresponding with the wiper blades 22¹ are the segmental contact carrying strips 24, 25, 26 as illustrated in Figs. 17 and 18. The strips 24, 25 and 26 have extensions in the form of contact segments 24¹, 25¹, 26¹ and 24². The contact segments 24¹, 25¹ operate in connection with the upper surface of the wiper blade 22¹. The strip 24 is connected to its respective binding post 24³ as illustrated in Fig. 3 and the segment 26 is connected to the terminal 13² through the clamping screw 27 and strip 15¹. The contact segments 26¹ and 24² operate in connection with the bottom surface of the wiper blade 22¹. The strip 25 is connected to its respective binding post 25² as illustrated in Fig. 3. When the lever of the ignition switch M is moved to its position F the contact segments 25¹ and 24² are connected through the wiper blade 22¹, and when the ignition switch member is moved to its position G, the contact segments 24¹ and 26¹ are connected through the wiper blade 22¹. The strip 25 has an extension in the form of an arcuate contact strip 25³ which co-operates with the wiper 31 of the starting switch SS. A companion contact strip 32 arcuate in shape, also operates in connection with the wiper 31. The segment 32 is connected to its respective binding post 32¹ as illustrated in Fig. 3.

For controlling the lighting and ignition switches L and M, I provide the handles or levers 28, and 29 fastened to their respective shafts 4 and 4¹ by means of the screws 30.

In order to yieldingly hold the lighting and ignition switch members L and M in any of their operated positions, I provide a holding device T (Fig. 20) which comprises a centrally pivoted member 33 which carries the rotatable rollers 34 and 35 in its bifurcated ends, the said rollers 34 and 35 operating in connection with their corresponding notched disks 8 and 8¹. The member 33 is pivotally supported at its center by a stud 36, which is suitably fastened to the plate 1 preferably by having the end that protrudes through the plate 1 threaded to receive the nut 37. The free end of a spring 38 rests against the bridge of the member 33, the other end of the spring 38 being fastened to the plate 1 by means of the screw 39 and nut 40, the spring pressing the rollers 34, 35 against their respective disks 8 and 8¹. When one of the switch members is operated the teeth of its disk are rotated against the rollers 34 or 35 as the case may be and due to the action of the spring 38, and as the disk advances, the roller acts upon the next toothed notch so as to give a snap action to the switch member and at the same time hold the actuating members of switches L and M in place. The cap 73 encloses the apparatus, this cap at the same time holding the members L and M in position upon their respective studs 2, 2¹. The cap is placed over the apparatus before the levers 28 and 29 are attached to their respective switches and before the knob 56 is placed upon the shaft 50 of the dimmer switch. The stud 36 has a shoulder 36¹ which rests against the member 33 to keep

it in position with the disks, the bottom of the member 33 bearing against the plate 1. The starting switch SS works in connection with the ignition switch M, a plate 41 (Fig. 20) being provided and having a bearing 42 attached to it in any suitable manner and being of such a size as to fit the extension 36² of the stud 36. The plate 41 also carries a roller 43 by means of a pin 44. The 10 roller 43 operates in connection with the cam 23 (Fig. 11), the said cam 23, as already described, being mounted upon the ignition switch operating member. An extension 41¹ of the plate 41 has a notch 41² to receive one end of a restoring spring 45, the other end of the restoring spring being placed in a notch 46¹ of the washer 46 which is held in place by the clamping screws 47 as illustrated in Figs. 4, 7 and 11. An 20 opening 41³ is provided in the enlarged portion of the plate 41 to allow the shaft of the dimmer switch to pass through. The wiper 31 is insulatingly mounted upon the plate 41 being fastened thereto by means of 25 rivets 48.

The starting switch may be operated when the ignition member M is in either its battery position F or magneto position G. When moving the ignition switch to its 30¹ battery position an added upward pressure (Fig. 11) upon the lever 29 forces the roller 43 to ride upon the cam surface 23¹ of the cam 23, the plate 41 swinging upon its pivot and carrying the wiper 31 with it from between the contact segments 25³ and 32 and placing said wiper 31 between the contact segments 13⁴ and 49 which operation will be further described in connection with Fig. 23.

40 Fig. 11 illustrates the starting switch in its operated position when the ignition switch is moved to its battery position F, but the starting switch may also be operated when the ignition switch is moved to its magneto position G. Added downward pressure upon the lever 29 forces the roller 43 to ride on the cam surface 23² of the cam 23 thus operating the switch SS as before described. When the pressure is released 50 the spring 45 restores the plate 41, thus restoring the starting switch to its actuated battery position or magneto position, as the case may be. The wiper 31 again rests in its normal position between the contact strips 25³ and 32.

Now referring to the dimmer switch illustrated in section in Fig. 22, it comprises a shaft 50 having an enlarged portion 50¹ upon which the stop 51 is mounted, the 60 stop 51 having two notches 51¹ and 51² which notches co-operate with the locking mechanism to lock the dimmer switch in either its normal or operated position. The stop has an arm 51³ which works to the 65 right or left in a V-shaped groove 52 in

plate 1, the arm 51³ being thus limited in its movement to the right or left by engaging the edges 52¹ or 52² of the groove 52, (Fig. 12). The wiper 16 of the dimmer switch is insulatingly mounted upon the shaft 50, 70 being clamped on said shaft by means of the nut 53. The portion of the shaft 50 extending through the plate 1 is drilled and tapped to receive a screw 54; a tension washer 55 being placed between the screw 75 54 and a washer, the tension washer 55 allowing the dimmer switch to be easily operated to the right or left but thereby held in its operated position. A knob 56 is suitably fastened to the stud 50. 80

A locking arrangement is provided whereby the lighting and ignition switches L and M may be locked in different positions and I therefore provide a Yale tumbler lock V, fastened to the cap 73. As illustrated in Fig. 21, this Yale lock is modified by the addition of a pin 57, which is eccentrically disposed on the cylinder 58 of the lock so that when the key 59 is turned the pin moves about the center of the cylinder 58. A connecting mechanism is provided between the lock and the switch members whereby the actuating members of L, M, DS and SS can be locked. I therefore provide the sliding plates 60 and 61 which 90 are held in the plate 1 by means of the shoulder screws 62 and 63 which extend through slots 60¹ and 60² and through the plate 1 into the nuts 64. The plates 60 and 61 are connected to each other by means of the stud 65. The plate 60 is a U-shaped member having the extended portions resting in grooves 66 and 67 and also having projections 60³ and 60⁴ which co-operate 100 with the disks 8 and 8¹ respectively to lock 105 the switch members.

I have preferably arranged the ignition switch so that it can only be locked in its inoperative position and therefore I have provided a single slot 8² in the disk 8¹ while the disk 8 has four slots 8³, 8⁴, 8⁵ and 8⁶ whereby the lighting switch may be locked in its normal or any of its three operative positions. The arm 8⁷ of the disk 8 limits the movement of the lighting switch member in its normal position, the said arm 8⁷ 110 engaging the extension 60³ of the plate 60 but when in its position D, the curved portion of the arm 8⁷ engages the roller 34 to limit its forward movement. To limit the 115 movement of the ignition switch in its operative position F, the curved surface 8⁸ of the disk 8¹ engages the roller 35 limiting the movement in this direction, and when operating the starting switch SS by lever 29 when in its position G, the surface 8⁹ 120 engages the extension 60⁴ of the plate 60. The plate 61 is connected to the plate 60 and rests in a guiding groove 68 and has an extension 61¹ which is adapted to move 130

into the notches 51¹ or 51² of the dimmer switch when the lock is operated to prevent the dimmer switch from being moved.

In Fig. 12 I have shown the locking mechanism and operating members of switches L and M in their normal positions and in Fig. 13, I have shown the locking mechanism operated and the operating members of L and M and dimmer switch 10 in their normal positions.

I also provide a horn cut-out HC which is operated in connection with the locking mechanism. The plate 61 is provided with a slot 61² having at its lower end an angular surface 61³ (Fig. 9) which co-operates with an insulating button 69 carried by the spring 70. The spring 70 is fastened to the plate 1 by means of the screws 71 which connect the spring to its terminals 13³ illustrated in Fig. 3. The spring 70 carries a contact 70¹ which is normally closed with a contact 72 which is connected to a terminal 72¹ as shown in Fig. 9. To operate the horn cut-out, the lock in operating carries the plate 61 upward, the button 69 riding upon the angular surface 61³ and opening the contacts 70¹ and 72.

The spring 70 by its button 69, which lies in the path of travel of the plate 61 and cooperates with the angular surface 61³ of said plate prevents the locking mechanism from being accidentally displaced and from rattling which might otherwise very readily occur from jarring. When the key is turned to locked position, the spring 70 also holds the locking mechanism, yieldingly in position, the button 69 then engaging the surface of the plate 61.

Assuming now that the ignition switch M is in its position F and the lighting switch member is in any of its operative positions, if the key is inserted in the lock and an attempt made to operate the lock, the key can be turned just a trifle or until the projection 60⁴ of the plate 60 will come in contact with the periphery 8¹⁰ of the disk 8¹. The key cannot be withdrawn and this unsuccessful attempt to turn the key will immediately indicate to the operator that the ignition member M is in an operative position. To lock the two switches L and M, the member M must be moved back into its inoperative position E. When in this position the notch 8² registers with the projection 60⁴ of the plate 60 and the key can now be turned. The pin 57 turns with the cylinder 58, the pin working in the opening 160 of the plate 60 moving the projection 60⁴ into the notch 8² of the disk 8¹ and moving the projection 60³ in any one of the notches 8³, 8⁴, 8⁵ or 8⁶ depending in which position the switch L is. It can be seen from the above that the lighting member can be locked in any of its positions when the member M is in its position E, but the

switch M can be locked only when in its position E.

The locking of the switch M of course prevents actuation of the starting switch SS, and the movement of slides 60, 61 will 70 lock the dimmer switch DS in either one of its positions.

In Fig. 23, I have illustrated a circuit arrangement adapted to operate in connection with the switch described, the 75 switch parts being shown diagrammatically and in their normal positions, like reference characters denoting like parts so that the description of the operation may be easily followed.

Referring now to the ignition switch M, I have shown it connected with an ignition circuit IC comprising an interrupter 73, a distributor 74 connected to four spark plugs 75, an induction coil 76, a battery 77, an ignition relay 78, and a second or magneto charged battery 86.

The general operation of the ignition switch is as follows: Assuming that the ignition switch M is in position F, and the 90 engine running, each time the contacts 79 and 80 of the interrupter are closed, and the distributor 74 connected to one of its contacts, a circuit is closed through the low 95 resistance winding 82, (winding 81 being normally short circuited through contacts 32, 25³ and 83) and through the contact strips 24² and 25¹. The operation of the relay 78 causes the interruption of its normal contact 83, whereby the energizing circuit 100 is broken through the low resistance winding 82 and primary of induction coil 76 to effect a spark at the connected spark plug, the relay 78 then being held energized through its high winding 81 until the contacts at the interrupter are broken, when the relay restores being again energized each time the interrupter contacts and the distributor contacts close.

Now if the ignition switch M is in its position G, with the contacts 24¹ and 26¹ connected, each time the interrupter contacts 84 and 85 and the distributor contacts are closed, a spark is effected at the connected 110 spark plug by current from the storage battery 86, which battery, (in the well-known Delco system) is charged by generator T, the charging connections of which are not shown here. The ignition relay 78 is not used in connection with the switch M in its so-called magneto position, as the current 115 from the magneto charged battery 86 preferably flows direct through the primary winding of the induction coil, and depends upon the break at contacts 84, 85 to produce the spark.

Now if the engine is not running and the operator wishes to start it, he throws the ignition switch M in either its position F or G. When thrown in position F further 120

pressure applied to the lever 29 moves the starting switch 85 to its alternate position to connect the wiper 31 across the contacts 13¹ and 49. The opening of contacts 32 and 25² interrupts the energizing circuit of the high resistance or holding winding 81 of relay 78, but low resistance winding 82 is still in circuit to be energized and as the contact 83 is included in the circuit of winding 82, the armature of relay 78 vibrates rapidly to produce a plurality of sparks for starting the engine. The closing of the contacts 13¹ and 49 by the additional movement of switch M closes a circuit for the starting 10 motor T from battery 86, thus starting the engine which is connected to the motor as in the well-known Delco self-starting system. As soon as the pressure on lever 29 is released by the operator, the wiper of the 15 ignition member M again assumes its position connecting the contacts 24² and 25¹, thus again connecting the ignition relay 78 in the uni-spark system.

When the switch member of M is moved 20 to its position G and added downward pressure applied to the lever 29, the contacts 13¹ and 49 are again closed, as before connecting battery 86 to motor T which rotates and starts the engine. In this case the battery 25 86 is used directly through the primary winding of the induction coil for producing the ignition sparks.

Now as to the lighting switch L. I have 30 illustrated a lighting system in connection with it, comprising the head lights H, the side lights S, and the tail and speedometer lights W and P, the battery 86, and the protective fuses 87, 88, and 89. I show a horn 35 90 in circuit with a horn cut-out HC, and a button 91 for operating the horn. When the switch member 28 is moved to its position B, the side lights, and tail and speedometer lights are lighted, the wiper blade 6¹ having its segments 6² in contact with the 40 contact segments 11¹ and common segment 13¹, segment 6⁴ then being in contact with the contact segment 10¹ and common segment 13¹. The circuit of the side lights extends from battery 86 to the contacts 10¹ 45 and 13¹, and wiper blade segments through the said lights in multiple through the protective fuse 88 to ground, and the circuit for the tail and speedometer lights extends from battery 86, contacts 11¹, 13¹ the segment 6⁴ 50 of the wiper through the tail and speedometer lights through the protective fuse to ground. The tail and speedometer lights are preferably in series so that the operator can tell from the speedometer light whether the 55 tail light is lighted. Now when the lighting switch member 28 is moved to its position C, the tail and speedometer and head lights are lighted, the wiper blade 6¹ having its segment 6² in contact with contact segments 60 12¹ and 14¹, and the segment 6⁴ in contact 65

with the contact segment 11¹ and common segment 13¹. The dimmer switch may be used in connection with the head lights H and when the wiper of the dimmer switch is in its ineffective position, the current for lighting said head lights passes through the resistance 21 to dim the head lights. The circuit extends from battery 86, through the resistance 21, the contacts 12¹ and 14¹, the wiper segment 6¹ and through the head lights and fuse to ground. This dimming arrangement does not affect the tail and speedometer light as the segment 6¹ is insulated from the segment 6⁴. The circuit of the tail and speedometer light is the same as described when the actuating member of L is in its position B.

When the wiper 16 of the dimmer switch DS is moved into engagement with the contacts 17, 14², resistance 21 is short circuited allowing the full current to pass through the head lights. The current through the head light also passes through a protective fuse 89. When the operating member of L is thrown to its position D, all of the lights are lighted, the wiper blade 6¹ then being in contact with the contact strips 10¹, 11¹ and common strips 13¹, and the segment 6⁴ of the wiper blade 6¹ in contact with the contact strips 12¹ and 14¹. The dimmer switch is used for dimming the head lights when the lighting member is in either its operated position C or D. When in its position D, the dimming of the head lights is the same as that described when the operating member of L is in its position C.

The particular embodiment of my invention as disclosed herein has been worked out particularly for commercial use but, I 105 contemplate applying my invention in other ways than that shown as it is apparent that many changes and modifications will readily suggest themselves and therefore I do not desire to be limited to the exact structure 110 as shown and described but aim to cover all that which comes within the spirit and scope of the appended claims.

Having described my invention what I claim as new and desire to secure by United 115 States Letters Patent is:

1. A combination switch including an ignition switch, a mounting plate for supporting said switch, normal and operative positions for said ignition switch, a so-called starting switch provided with an operating member also supported by said mounting plate, and mechanical co-operating means including a cam attached to said ignition switch and a roller carried by said operating member for connecting said starting and ignition switches whereby said ignition switch when actuated in its operated position controls the operation of the starting switch, said operating member being 120 125 130

unmovable until said ignition switch has been moved to its operative position.

2. A combination switch including an ignition switch provided with an actuating member having a plurality of operative positions, spring means for holding said actuating member in any of its operative positions, a starting switch having co-operating contacts, operating mechanism independent of but in mechanical relation to said actuating member for associating the contacts of said starting switch with said actuating member, said actuating member being adapted to be moved to any of its operative positions and then to receive the continued movement to operate said connecting mechanism to operate said starting switch contacts, and spring means for returning said starting switch to its normal position when pressure is released from said actuating member.

3. A combination switch including an ignition switch provided with an actuating member having a plurality of operative positions, spring means for yieldingly holding said actuating member in any of its operative positions, a starting switch provided with an operating member having a normal and an operative position, spring means for returning said operating member to its normal position when moved therefrom, and mechanism including a cam attached to said actuating member and a roller attached to said operating member for moving said operating member from its normal to its operative position when said actuating member is moved to one of its operative positions and the movement thereof continued.

4. A combination switch including an ignition switch provided with an actuating member having a plurality of operative positions, an operating member for controlling a starting switch having co-operating contacts, means whereby the actuating member for said ignition switch when moved to either of its operative positions may be operated to actuate the said operating member to cause the co-operation of said starting switch contacts, and a locking member for locking said actuating member against actuation.

5. A combination switch including an ignition switch having an actuating member, a starting switch having an operating member for controlling co-operating contacts, means including said actuating member and said operating member for mechanically connecting said switches whereby the operation of the actuating member for said ignition switch after it is moved to its effective position effects the co-operation of said starting switch contacts, and a locking member for locking said switches against actuation.

6. A combination switch including an ignition switch provided with an actuating

member having a normal and an operative position, a starting switch provided with co-operating contacts controlled by an independent operating member, means whereby the actuating member for said ignition switch after being moved to its operative position may be operated to actuate the said operating member to effect the co-operation of said starting switch contacts said operating member remaining stationary until said actuating member has moved the ignition switch to its operative position, and spring means for returning said operating member to normal when pressure is released from said actuating member.

7. A combination switch comprising a mounting plate, ignition, lighting and starting switches having contact elements peripherally mounted upon said plate, a pivoted contact operating device for each of said switches intra-peripherally disposed with relation to said contact elements, an actuating member for controlling the operating device of said lighting switch, a second actuating member for controlling the operating devices of said ignition and starting switches, and a common member for locking said switches against actuation.

8. A combination switch comprising ignition, lighting and starting switches having radially disposed contact elements, a centrally positioned pivoted contact operating device for each of said switches, radially extending contact elements for each of said pivoted devices for co-operating with the corresponding contact elements, an actuating member for controlling the contact operating device of said lighting switch and a second actuating member for controlling the contact operating devices of said ignition and starting switches, and a common locking member co-operating with said ignition and lighting switches for preventing effective movement of any of said switches.

9. A combination switch comprising ignition, lighting, starting, and dimmer switches having contact elements radially disposed and lying in parallel planes, a relatively centrally disposed contact operating device for each of said switches, contacts for each of said devices for co-operating with the corresponding contact elements, actuating members for controlling the operating devices of said ignition, lighting and dimmer switches, means controlled by the actuation of said ignition switch for actuating the operating device of said starting switch, and a locking member for preventing the effective movement of said actuating members.

10. A combination switch comprising ignition, lighting, starting and dimmer switches having radially disposed contact elements, a pivoted contact operating device for each of said switches centrally disposed with rela-

tion to the corresponding contact elements, a radially extending contact element for each of said pivoted devices for co-operating with its corresponding contact elements, actuating members for controlling the operating devices of the ignition, lighting and dimmer switches, means controlled by the actuation of said ignition switch for controlling the operating device of said starting switch, and a locking member for preventing the effective movement of said actuating members.

11. A combination switch comprising independently operable ignition and lighting switches, a starting switch, operating mechanism connecting said starting and ignition switches whereby the operation of said ignition switch effects the operation of the starting switch, and a common locking device operable only when said ignition switch is in its normal position, for locking all of said switches against actuation.

12. A combination switch comprising independently operable ignition, lighting and dimmer switches, a starting switch, operating mechanism connecting said starting and ignition switches whereby the operation of said ignition switch effects the operation of the starting switch, and a common locking device operable only when said ignition switch is in its normal position, for locking all of said switches against effective operation.

13. An electrical switch combination having two switch contacts each having an idle and an operated position, a lock operable only when one of said contacts is in its idle position, but when said other contact is in either of its positions, and an auxiliary switch contact operated by said lock.

14. An electrical switch having a movable wiper for controlling the ignition circuit and a second movable wiper for controlling the lighting circuits, a lock common to both of said wipers, means for preventing the operation of said lock unless the ignition wiper is in its off position, and a set of contacts operated by said lock mechanism.

15. A combination switch comprising an ignition switch and a starting switch, an actuating member for said ignition switch, an operating member for said starting switch for controlling switch contacts, means for moving said actuating member to cause said operating member to actuate said switch contacts, a common locking mechanism for locking said switches against effective operation, and an auxiliary switch contact controlled by said common locking mechanism.

16. A combination switch including an ignition switch and a starting switch, an actuating member for said ignition switch, switch contacts, an operating member for said starting switch for controlling said switch contacts, means for moving only said actuating member whereby said ignition switch is

moved to an operative position, said actuating member now being in position to actuate said operating member to cause said switch contacts to be actuated upon a further movement of said actuating member, and a locking member for preventing effective actuation of said ignition and starting switches.

17. A combination switch including an ignition switch and a starting switch, a cam member for said ignition switch, an operating member for said starting switch provided with a roller independent of but in mechanical relation with said cam member, a movable contact maker for each of said switches, an actuating member for said ignition switch for moving only said movable ignition contact maker into an operative position, said actuating member adapted upon further movement thereof to cause said cam member to actuate said operating member by contact with said roller to move said movable starting switch contact maker into an operative position.

18. A combination switch comprising an ignition switch provided with a controlling member having a normal and an operative position, spring means for yieldingly holding said controlling member in either of its said positions, a starting switch provided with an independent operating member in mechanical relation with said controlling member having a normal and an operative position, a movable switch contact maker for each of said switches, an actuating member adapted upon initial movement to move only the ignition switch contact maker into its operative position but for thereafter bringing said controlling member into operative relation with said operating member to move said starting switch contact maker into its operative position, and spring means for returning said operating member to its normal position when pressure is released from said controlling member.

19. A combination switch comprising an ignition switch including an actuating member, a so-called starting switch provided with an independent operating member for controlling co-operating contacts, operating mechanism including said operating member for connecting the contacts of said starting switch with said actuating member, a normal and an operative position for said actuating member, spring means for yieldingly holding said actuating member in its normal and operative positions, and means for moving only said actuating member to its operative position and for then moving it beyond said operative position against the tension of said spring means whereby said operating member moves said starting switch contacts.

20. A combination switch comprising ignition, lighting and dimmer switches each having normal and off-normal positions,

- means for operating each switch independently of the other, a plurality of off-normal positions for said lighting and ignition switches, and means including a common locking mechanism for locking said lighting and dimmer switches in their normal or off-normal positions, said means being operable only when said ignition switch is in its normal position. 5
- 10 21. A combination switch of the character described comprising ignition, lighting and dimmer switches each having a normal and an off-normal position, means for operating each switch independently of the other, 15 a plurality of off-normal positions for said lighting and ignition switches, and means including a common locking mechanism for locking said lighting and dimmer switches in any of their positions, said means being 20 operable only when said ignition switch is in its normal position.
22. A combination switch of the character described comprising ignition, lighting and dimmer switches, each having a normal and an off-normal position, means for operating each switch independently of the other, a plurality of off-normal positions for said lighting and ignition switches, and means including a common locking mechanism for 25 locking said lighting and dimmer switches in any of their positions, said means being operable only when said ignition switch in 30 its normal position.
23. A combination switch comprising a lighting switch and an ignition switch, pairs of stationary contacts and a movable contact maker for said lighting switch, a starting switch also provided with a pair of stationary contacts and a movable contact maker, 35 said stationary contacts being circumferentially disposed and lying in parallel planes, a common connecting strip forming one contact for each of said pairs of contacts, and means comprising actuating members for 40 said lighting and ignition switches for moving said contact makers into position to connect said common contacts with their associated contacts.
24. A combination switch comprising a mounting plate, ignition, lighting and starting switches having contact elements peripherally mounted upon said plate, a pivoted contact operating device for each of 45 said switches intra-peripherally disposed with relation to said contact elements, an actuating member for controlling the operating device of said lighting switch, a second actuating member for controlling the operating devices of said ignition and starting switches, and a common holding member 50 for yieldingly holding said ignition and lighting switches.
25. A combination switch comprising an ignition switch, a dimmer switch and an auxiliary switch, means including a lock- 55 ing plate for locking said ignition switch against actuation, and a locking member attached to said locking plate for locking said dimmer switch against actuation and for operating said auxiliary switch. 70
26. An electrical switch combination having manually controllable switch contacts, an auxiliary switch including a flexible spring contact, a locking plate adapted to be operated to effectively lock said manually 75 controllable switch contacts against actuation, and a buffer operated by said locking plate for moving the said flexible spring contact of said auxiliary switch.
27. An electrical switch including an ignition switch, a lighting switch and an auxiliary switch, a slidable locking plate for locking said ignition and said lighting switches against actuation, a flexible spring contact for said auxiliary switch, and a 80 member of insulating material attached to said flexible spring contact and adapted to be operated by said slidable locking plate to actuate said auxiliary switch.
28. A switch comprising a base having 85 contacts, a rotor switch member having contact means for engaging said contacts, a removable key for controlling the actuation of said switch member, and other switch contacts actuated by the removable key when 90 fully inserted and rotated in a clockwise direction, said other contacts being also actuable by said key when fully inserted and rotated in the opposite direction.
29. In a combination switch, a removable 95 handle, switch contacts, a movable member in cooperation with said switch contacts, said movable member being controlled by said handle, and other switch contacts controlled by the turning of the attached 100 handle in a clockwise direction and in a 105 counterclockwise direction when being used to control said movable member.
30. In a combination lighting and auxiliary switch, a key controlled lighting switch, 110 and an auxiliary switch actuated by the complete insertion of the key and the rotation of the same in a clockwise direction to control the lighting switch, said auxiliary switch being also actuated by the rotation of the key 115 in a counterclockwise direction to control the lighting switch.
31. A combination switch including a lighting switch, a supplementary switch, 120 said supplementary switch adapted to be actuated by the turning of the key to lock the lighting switch and by the turning of the key to unlock the lighting switch.
32. A switch comprising a base having 125 contacts, a rotary switch member having contact means for engaging the contacts, a removable key for controlling the actuation of said switch member, and other switch contacts actuated by the key when the key is rotated in a clockwise direction to control the 130

switch member and when the key is rotated in a counterclockwise direction to control the switch member.

33. In an electric switch, a plurality of circuit contacts, a switch arm engageable with said contacts in succession, a supplementary switch, and mechanism constructed and arranged to lock said switch arm in any of its successive positions and to simultaneously actuate said supplementary switch, said mechanism being also arranged to unlock said switch arm and to simultaneously actuate said supplementary switch.

34. In an electric switch, a plurality of circuit contacts, a switch arm engageable with said contacts in succession, a supplementary switch, and mechanism including a removable key which, upon being turned to the position in which it may be removed, locks said switch arm in any of its successive positions and simultaneously actuates said supplementary switch, said mechanism being also arranged so that when said key is turned in the opposite direction to unlock said switch arm it simultaneously actuates said supplementary switch.

35. In an electric switch, a rotatable switch shaft adapted to be set to various positions, a plate movable with said switch shaft, a supplementary switch, and a member constructed and arranged to lock said plate and switch shaft in any position to which the switch shaft may be set and to simultaneously actuate said supplementary switch, said member being the sole means for operating said supplementary switch.

36. An electric switch comprising a plurality of contacts adapted to be connected to different circuits, a switch arm movable to any one of a plurality of positions to engage said contacts and control the circuits connected thereto, a second switch arm and contact adapted to be connected to a circuit, key-actuated devices for operating said second switch arm and simultaneously locking the first switch arm against movement to a new position, said key actuating device being also operable for unlocking said first switch arm and for simultaneously actuating said second switch arm, and a key for actuating said devices.

37. An electric switch comprising a plurality of contacts adapted to be connected to different circuits, a switch arm movable to any one of a plurality of positions to engage said contacts and control the circuits connected thereto, a second switch arm and contact adapted to be connected to a circuit, a key operated rotatable locking device for the first switch arm, means for operating the second switch arm by the rotation of the locking device to locking position and upon the rotation of the locking device to an unlocking position, and means for sustaining

the key in position for operating said rotatable locking device.

38. A device of the character described including a front plate and a rear plate, circuit controlling switches secured between said plates, a pin tumbler lock secured to said front plate, a projecting key plug for said lock, and means operable by said key plug for locking said switches against actuation.

39. An electrical switch comprising an adjustable switch member, and contacts arranged to be switched to different relations by means of said member, mechanism for locking said member against actuation including a key-operated lock, a pair of elements, the one having a surface inclined to a surface of the other, and spring means maintaining said surfaces, the one in the path of the other to yieldingly maintain said locking mechanism in position.

40. An electrical switch including a base, a front plate and a rotatable contact maker, a contact for engagement by said contact maker and carried by the base, means for fastening said base to said front plate to operatively relate said contact and said contact maker, a serrated member and a spring-pressed member for holding said contact maker in its various positions, a slidable locking plate for preventing movement of said contact maker, a lock and a lock barrel therefor having a member for cooperating with said slidable locking plate and spring means cooperating with said slidable locking plate tending to maintain said locking plate in either of its positions.

41. An electrical switch including a front plate and a back plate, relatively stationary contacts carried by the back plate, a contact maker to engage said contacts having an actuating element extending through said front plate, locking mechanism operated through said front plate including a movable locking member for preventing movement of said contact maker, and spring means cooperating with said movable locking member tending to hold said member in either of its positions.

42. An electrical switch comprising a manually adjusted switch member, locking mechanism to lock said switch member against actuation including a manually adjusted locking element, spring means for yieldingly maintaining said switch member as adjusted, and spring means for yieldingly maintaining said locking element in either of its positions.

43. An electrical switch comprising an adjustable switch handle and contacts arranged to be switched to different relations by means of said handle, mechanism for yieldingly holding said switch in said different switching relations, said mechanism

- including a pair of elements the one having a surface in contact with a surface of the other, and spring means pressing said surfaces together, locking mechanism including 5 a part of said switch for engagement by said mechanism to hold said switch against actuation by said handle, and a spring controlled element for yieldingly maintaining said locking mechanism in unlocking position.
44. An electrical switch including manually movable contact maker, and a relatively stationary contact for engagement thereby, an element and an inclined plane 10 spring-pressed together holding said maker in various positions; means for preventing adjustment of said contact maker to operatively engage said contact, said means including a key and a lock barrel operated thereby, and spring means tending to resist the turning of said barrel by said key.
45. An electrical switch including a manually adjustable contact maker and a relatively stationary contact adapted to be engaged thereby, spring means for yieldingly holding the contact maker in its different positions, independently manually adjustable locking mechanism for adjustment to permit or prevent the adjustment of said 15 contact maker and spring means preventing rattling of said locking mechanism when in unlocking position.
46. An electrical switch including a manually adjusted switch member and a contact 20 adapted to be closed by the operation of said member, a key-operated lock for locking said member against actuation; a slideable plate actuated by said lock in locking said member, and an element frictionally contacting with said slideable plate upon actuation to yieldingly resist the operation of 25 said lock.
47. An electrical switch including a manually adjustable member and contacts adapted 30 to be switched to different relations by means of said member; a key operated lock for locking said member against actuation and a friction device tending to prevent the turning of said key in locking said device.
48. An electrical switch including a manually adjusted switch member and contacts adapted to be switched to different relations by means of said member, a key operated lock for locking said member against actuation; a slideable plate cooperating with 35 said lock, a pair of surfaces, one inclined to the other, and one of said surfaces spring-pressed in the path of the other to yieldingly resist the movement of said plate when turning of said key is initiated, and friction means to yieldingly resist the movement of said plate on the further turning of said key.
49. A combination switch having an on and off position, a key operated lock for 40 preventing actuation of said switch, and an auxiliary switch actuated upon the turning of the key operated lock to lock said first switch and also upon the turning of the key operated lock to unlock said first switch.
50. A combination switch for an automobile or the like provided with a switch adapted to be moved to a plurality of different positions, a key operated lock for said switch, and a second switch actuated when the key operated lock is rotated to lock said first switch and also upon the rotation of the key operated lock to unlock said first switch.
51. A combination switch including a switch adapted to be moved to a plurality of 45 positions, a locking member for preventing actuation of said switch, a second switch, and means controlled by said locking member, when said member is moved to a position to lock said first switch, for actuating said second switch and for actuating said second switch when said locking member is moved to unlock said first switch.
52. A combination switch including a lighting switch, a supplementary switch, and locking means operable to actuate said supplementary switch when said first switch is locked against actuation and to actuate said supplementary switch when said first switch is unlocked for actuation.
53. A combination switch including a lighting switch, an auxiliary switch, and key operated means for locking and unlocking said first switch, said key operated means being also adapted to actuate said auxiliary switch upon the locking of the first switch and also upon the unlocking of said first switch.
54. A combination switch including a lighting switch and a supplementary switch 50 for automobiles or the like, a removable actuating member for said supplementary switch, and means controlled by said actuating member for locking and unlocking said lighting switch and for simultaneously opening and closing said supplementary switch.
55. A combination switch including a lighting switch and an auxiliary switch, means for locking and unlocking said lighting switch and for opening and closing said auxiliary switch, and a removable member for actuating said means to simultaneously lock said lighting switch and to open said auxiliary switch and to unlock said lighting switch and to close said auxiliary switch.
56. A combination switch including a lighting switch and a supplementary switch, means for locking and unlocking said lighting switch and for opening and closing said supplementary switch, and a removable member adapted when inserted in position and rotated in one direction to simultaneously lock said lighting switch and open

- 5 said supplementary switch with a continuous movement and to simultaneously unlock said lighting switch and close said supplementary switch with a continuous movement 5 when operated in the reverse direction.
57. A combination switch provided with a front plate and a rear plate, a switch mounted between said plates, an auxiliary switch between said plates, a removable actuating member extended through said front plate for locking and unlocking said first switch and for opening and closing said auxiliary switch. 75
58. A device of the character described 15 including a front plate and a back plate, a switch secured between said plates, operating means extending through said front plate for controlling said switch, an auxiliary switch, and a key actuated member for locking and unlocking said first switch and 20 forming the sole means for actuating said auxiliary switch.
59. A combination switch, a key operated lock therefor, and a second switch operated 25 exclusively by the key actuating movement of the lock.
60. A combination switch including a lighting switch operating means for actuating said lighting switch, a supplementary 30 switch, and key operating means for preventing movement of said lighting switch and forming the sole means of operation of said supplementary switch.
61. A switch comprising a base having 35 contacts, a rotary switch member having contact means for engaging said contacts, a removable key for controlling the actuation of said switch member, and other switch contacts actuated exclusively by the removable key. 100
62. In a combination switch a removable handle, switch contacts, a movable member for cooperation with said switch contacts, said movable member being controlled by 45 said handle, and other switch contacts controllable only by the turning of the attached handle. 105
63. A combination switch including a key controlled lighting switch and a supplementary switch actuated exclusively by said key. 110
64. A lighting switch and a supplementary switch for automobiles or the like, a removable handle, said removable handle forming the exclusive means for actuation of said supplementary switch, and means controlled by said handle for rendering said lighting switch inoperable. 115
65. A switch comprising a base having 55 contacts, a rotary switch member having contact means for engaging said contacts, a removable key for controlling actuation of said switch, and another switch contact actuatable only by said key. 120
66. In an electric switch, a plurality of 60 circuit contacts, a switch arm engageable with said contacts in succession, an auxiliary switch, and mechanism constructed and arranged to lock said switch arm in any of its positions and forming the sole means to 70 actuate said auxiliary switch. 125
67. A switch provided with a casing, a movable contact member having actuating means extending through said casing, a supplemental switch, and a removable member 75 extending into said casing for preventing actuation of said movable contact member and forming the sole means of operation of said supplementary switch. 130
68. A device of the character described in- 80 cluding a plate, a switch mounted back of said plate and provided with actuating means extending through said plate, a second switch, and a removable member, controlling means for preventing actuation of 85 said first switch and forming the sole operating means for said second switch.
69. A device of the character described in- 90 cluding a plate, a pair of switches back of said plate, a removable member for preventing actuation of one of said switches and 95 forming the sole operating means for the other of said switches. 100
70. A device of the character described in- 95 cluding a casing a pair of switches in said casing, and a removable handle extending into said casing for preventing actuation of one of said switches and forming the sole operating means for the other of said switches. 105
71. A device of the character described in- 100 cluding a casing, a pair of switches in said casing, means entirely within said casing for preventing actuation of one of said switches and for actuating the other of said switches, and a key extending into said casing forming the sole means for actuating said means. 105
72. A device of the character described in- 110 cluding a rear plate having stationary contacts, a front plate, a switch arm for making contact with said stationary contacts, an operating member extending through said front plate for operating said switch arm, and a removable member for preventing actuation of said switch arm and forming the sole means of operation of said supplementary switch. 115
73. A device of the character described in- 115 cluding a front plate, a circuit controlling switch mounted at the rear of said plate, a pin tumbler lock having a casing and a key plug extending forwardly into an opening of said plate, a member provided with an orifice integrally formed at right angles with said casing for engaging the rear face of said plate, a screw for engaging said orifice in said member and having screw-threaded engagement with said plate for maintaining said lock in position, a locking member positioned at the rear of said plate, a 120
- 65

cylindrical member secured to said key plug and adapted to engage said locking member and travel with said key plug to effect the operation of said locking member to lock said circuit controlling switch.

74. A device of the character described including a front plate provided with an opening, a circuit controlling switch back of said plate but operable from the front thereof, a pin tumbler lock having a casing and a key plug for engaging the opening of said plate, lugs integrally formed at right angles with said casing and adapted to engage the back of said plate, a screw for engaging an orifice in one of said lugs and having screw-threaded engagement with said plate to maintain said tumbler lock in its mounted position, a locking member movable in different directions positioned at the rear of said plate, a member having its one end secured to said key plug and its other end engaging said locking member, and a key for engaging said key plug to operate said plug whereby said last member moves said locking member to its different positions to lock and unlock said circuit controlling switch.

75. A device of the character described including a plate, a circuit controlling switch back of said plate but operable from the front thereof, a pin tumbler lock having a casing and a key plug located at the rear of said plate, the front end of said key plug extending forwardly into an opening of said plate, lugs integrally formed at right angles with said casing for engaging the face of said plate, a screw engaging an orifice in one of said lugs and having screw-

threaded engagement with said plate for maintaining said pin tumbler lock in its mounted position, a locking member having an "on" and an "off" position, a projecting element secured to said key plug at its one end and its opposite end engaging said locking member, a key for engaging said key plug to operate said key plug and said element to effect the movement of said locking member to its "on" or "off" position to lock and unlock said circuit controlling switch.

76. A device of the character described including a plate provided with a pair of openings, a circuit controlling switch provided with an operating member extending through one of said openings, a pin tumbler lock having a casing and a rotatable key barrel, engaging one of said openings in said plate, a member integrally formed at right angles with said casing and adapted to engage said plate, a screw for engaging an opening in said member and having screw-threaded engagement with said plate whereby said pin tumbler lock is secured in its mounted position, a member at the rear of said plate adapted to be moved to different positions, a key for rotating said key barrel whereby said element moves to effect the operation of said last member, to prevent movement of said circuit controlling switch.

Signed by me at Chicago, county of Cook and State of Illinois, in the presence of two witnesses.

WILLIAM KAISLING.
